STAND LAMP HAVING AN ILLUMINATED
BASE

James G. Zobian, Roslyn, N. Y.

Application June 23, 1950, Serial No. 169,929

3 Claims. (Cl. 240—81)

1

My invention relates to illuminated base lamps, and more particularly to a lamp of any desired construction, such as a table lamp or a floor lamp in which the base is illuminated interiorly thereof and in which a main or upper lamp is supported by the illuminated base in a novel, simple and safe manner to enable its ready removal for the purpose of changing the incandescent lamp in the base or for the purpose of replacing illuminated pictorial representations which are carried by the base.

Illuminated base lamps are known to the art and comprise usually a base formed with translucent or transparent sides which support the upper portion of the lamp which carries a main incandescent lamp or lamps and a lamp shade. The arrangement is controlled by a three-way switch whereby either the upper or lower lamp may be lighted, both lamps may be lighted, or both lamps may be de-energized. If the transparent or translucent sides of the base are in the form of pictorial representations, such as photographic slides either in black and white or in color, or other scenes shown on translucent parchment, paper or ground glass, or the like, care must be taken that the conductors delivering energy to the upper lamp do not throw shadows upon the scenes illuminated by the base lamp. It is desirable to permit the pictorial representations carried by the base to be changed. These considerations make it difficult to give ready access to the base when the incandescent lamp positioned therein becomes inoperative by the burning out or breaking of its filament, or otherwise. In order to give a pleasing design it is frequently desirable to mount the base on a small pedestal, and this construction renders access to the interior of the base even more difficult. The use of doors or access openings from the bottom of the lamp, furthermore, interfere with the mounting of the socket for the base lamp which should be positioned centrally of the bottom of the base in order to illuminate the sides of the base more evenly.

One object of my invention is to provide an illuminated base lamp in which the upper or main lamp is secured to the base in a readily removable manner in order to give access to the lamp in the base and to permit the ready removal and replacement of transparent or translucent pictorial representations mounted on the sides of the base.

Another object of my invention is to provide readily releasable means for securing the upper portion of an illuminated base lamp to

2

the base in such a manner that the securing means acts as the contact making means for the electrical path furnishing energy for the upper lamp.

Another object of my invention is to provide an illuminated base lamp having a removable upper portion carrying an upper lamp in which the upper lamp becomes immediately de-energized when removed from the base and in which the danger of short circuits or shocks to a person removing or replacing the incandescent lamp in the illuminated base socket is minimized.

Other and further objects of my invention will appear from the following description.

15 In the accompanying drawings which form part of the instant specification and which are to be read in conjunction therewith and in which like reference numerals are used to indicate like parts in the various views:

20 Figure 1 is a perspective view of a lamp showing one embodiment of my invention.

Figure 2 is a sectional elevation of the lamp shown in Figure 1 drawn on an enlarged scale.

25 Figure 3 is a top plan view of the base of the lamp with the upper assembly removed.

In general, my invention contemplates the provision of a base for a lamp having the sides thereof formed with picture frames. The lamp may have any desired cross-sectional shape, such as square, rectangular, hexagonal, octagonal, or the like. Each of the picture frames is provided with slots adapted to hold a pair of glass or transparent plastic plates, the outer of which may be clear and the inner of which may be frosted or translucent. A transparent or translucent pictorial representation such as a positive photographic print on film or upon glass in black and white or in colors, or a lithograph, or the like, may be mounted between the glass plates and framed by the sides of the base of the lamp.

30 A socket is mounted interiorly of the base of the lamp adapted to hold an incandescent lamp of any appropriate size. The base is supported in any suitable manner, as for example, by a pedestal into which passes a cable

35 carrying a pair of conductors and a three-way switch. The conductors are led upwardly of the base adjacent the corners of the base in a position clear of the pictorial representations framed by the base so as not to cast shadows or otherwise interfere with a clear view of the scenes displayed by the lamp base.

40 The conductors terminate in a pair of metallic re-entrant sockets positioned on opposite sides of the center of the top of the lamp base. A cover member having

45 a pair of spring pressed metal lugs is adapted

to seat upon the base with the spring lugs in contact with the socket members, securing the top to the base. A pair of conductors lead from the spring pressed lugs upwardly to the socket in which the upper lamp is mounted. Any suitable shade supporting means may be carried by the upper member for supporting a shade around the upper lamp. The three-way switch, such as is known to the art, is adapted to complete the circuit through both lamps in parallel, through the upper lamp alone, through the lower lamp alone, and to break the circuit to both lamps. If desired, separate switches may be employed for the upper and lower lamps without departing from the invention. The base may be made of any suitable material, such as metal, wood or plastic.

More particularly, referring now to the drawings, a pedestal 10, which may be formed of plastic or wood or the like, supports a base member 12. A threaded metallic sleeve 14 clamps the base 12 to the pedestal 10 by means of a pair of nuts 16 and 18 threaded exteriorly of the sleeve 14. A socket 20 for the base is supported by an insulating sleeve 22 carried by the upper end of the metallic sleeve 14. The socket 20 is adapted to hold an incandescent lamp 24 which illuminates the base. The sides of the base are made in the form of picture frames 26 adapted to hold outer transparent plates 28 which may be made of glass or transparent plastic, inner translucent plates 30 of glass or plastic, and transparent or translucent prints or photographs 32 which are interposed between the glass or plastic plates. The corners of the base are formed with vertically extending slots 34 into which the plates slide, as can be seen by reference to Figure 3. With the top removed, as shown in Figure 3, the plates can be readily slid into or out of the slots when it is desired to change the pictorial representations which are displayed, and ready access is also had to the base incandescent lamp 24. Vertically extending ducts 36 are formed in the base structure at diagonally opposite corners. These ducts communicate with horizontally disposed passageways 38 formed adjacent the top of the base, and with lower transverse passageways adjacent the bottom of the base. A cable 42 containing a pair of wires 44 and 46 is led into the pedestal 10 and is adapted to be fitted with a plug adapted to be inserted in a wall socket, as is known to the art. A conductor 48 is connected to conductor 44 and is led upwardly through the duct 36 and cross duct 38 and electrically connected to a metal member 49 having a re-entrant portion. The socket member 48 is secured centrally of one side of the upper portion of the base internally thereof. The conductor 46 is connected to a three-way switch 50 controlled by switch operating member 52. A conductor 54 leads from the three-way switch to one terminal of the socket 20. A conductor 56 is connected between conductor 44 and the other terminal of the socket 20. A conductor 58 leads upwardly through one vertical corner duct 36 to a second metallic socket member 60 positioned directly opposite the socket member 48. An upper member 62 is adapted to cover the base. It carries a pair of spring pressed plungers 64 and 66 adapted to coact with the socket members 48 and 60. The arrangement is such that when the member 62 seats upon the base, the spring pressed plungers 64 and 66 will register with the sockets 48 and 60, holding the cover member 62 upon the base and making electrical contact

respectively with the conductors 40 and 58. An upper lamp socket 68 is supported upon an externally threaded sleeve 70 which is secured to the member 62 by means of upper nut 72 and lower nut 74. The circuit to the socket 68 is completed by conductor 76 which is connected to the spring pressed plunger 64 and by conductor 78 which is connected to the spring pressed plunger 66. A shade supporting bracket 80 is carried by the sleeve 70 and is adapted to support a lamp shade 82 in any manner known to the art. An incandescent lamp 84 is mounted in the socket 68. The bottom of the pedestal 10 is closed by a plate 86 held in place by screws 88. In use, the upper member 62 is removed by lifting straight upwardly. The spring pressed plungers 64 and 66 will be cammed inwardly against the curved socket plates 48 and 60, allowing the ready removal of the upper member 62 and with it the upper lamp 84 and shade 82. The bottom surface 90 of the upper member is flat so that the upper member may be placed on a table or other surface in a convenient manner. The lamp shade need not be removed or disturbed. The removal of the upper member immediately disconnects the upper assembly from the source of power so that it is unlikely, should the switch operating member 52 be in a position energizing the socket members 48 and 60, for one removing the upper member to receive a shock. This is due to the fact that the socket members 48 and 60 are on opposite sides of the base at considerable distance from each other. The assembly of plates and pictorial representations 28, 32 and 30 may be removed as a unit from the vertical slots 34 either for cleaning of the glass surfaces or the replacement or change of the pictorial representations 32. While the top assembly is off, too, the lamp 24 may be inserted in the base socket with ease. The top assembly is replaced and the registration of the spring pressed plungers with the sockets will complete the circuit to the upper incandescent lamp 84. Assuming that the switch is in the off position, both lamps are de-energized. When the switch is first turned it will complete contact between conductor 44 and its connecting conductors 40 and 56 to both conductors 54 and 58, thus energizing both upper and lower lamps. The next position of the switch will disconnect the conductor 54 from the circuit, thus extinguishing the lower lamp 24 while leaving the upper lamp 84 energized. The next position of the switch will disconnect conductor 58 and connect conductor 54, thus extinguishing the upper lamp and illuminating only the base. A further rotation of the switch operating member 52 will bring the switch back to its initial position. It is understood, of course, that the three-way switch may be connected in any suitable manner so that the above operations may take place in any desired sequence. It will be seen that I have accomplished the objects of my invention. I have provided an illuminated base lamp in which the upper lamp assembly is secured to the base in a readily removable manner in order to give access to the incandescent base lamp and to permit ready removal and replacement of the pictorial representations mounted on the sides of the base. I have provided readily releasable means for securing the upper portion of an illuminated base lamp in such manner that the securing means acts as contact making means for the electrical conduction path furnishing energy to the

upper lamp. I have provided an illuminated base lamp in which the upper portion immediately becomes de-energized when removed from the base and in which the danger of short circuits or shocks during the operation of replacing the incandescent lamp in the base is minimized, irrespective of whether the base socket is energized or not.

It will be understood that certain features and subcombinations are of utility and may be employed without reference to other features and subcombinations. This is contemplated by and is within the scope of my claims. It is further obvious that various changes may be made in details within the scope of my claims without departing from the spirit of my invention. It is therefore to be understood that my invention is not to be limited to the specific details shown and described.

Having thus described my invention, what I claim is:

1. An illuminated base lamp including in combination a support, generally vertical side walls carried by the support to form a chamber open at its upper end, one of said side walls being formed with a window, means for mounting an electric lamp within the chamber, a second support having a depending portion removably telescoped within the chamber at its upper end, means for mounting a second electric lamp upon the second support, two electrically conductive securing means each formed of a pair of readily releasable interengageable means, one of the interengageable means of each pair being stationarily mounted on the side walls within the chamber adjacent its upper end, the other interengageable means of each pair being mounted upon the depending portion for coaction with the stationarily mounted interengaging means of each pair, a pair of conductors adapted to be connected to a source of potential for energizing the first electric lamp

mounting means, a pair of conductors for energizing the second electric lamp mounting means, said last named conductors terminating in electrical contact with the respective interengageable means carried by the depending portion of the second support, conducting means for connecting said first pair of conductors to respective stationarily interengageable means, the construction being such that when said interengageable means are engaged said second support will be releasably secured to said chamber and said second pair of conductors will be in electrical communication with respective first conductors.
